UNITED STATES PATENT OFFICE

OLIVER B. PARKER, OF NEW YORK, N. Y., ASSIGNOR TO PACENT ELECTRIC COMPANY, INC., OF NEW YORK, N. Y., A CORPORATION OF NEW YORK

PHONOGRAPH PICK-UP

Application filed January 7, 1929. Serial No. 330,764.

The objects of this invention are to provide an electric pickup for phonographs, which will be particularly simple, inexpensive, small and compact, light in weight and well balanced, so as not to wear on the record and in which the movable element will have a free but relatively short movement.

Various other objects and the novel features of construction by which the same are attained will appear in the course of the following specification.

The drawing accompanying and forming part of the specification illustrates one practical embodiment of the invention, but it should be understood that the structure may be modified as regards this disclosure without departure from the true spirit and broad scope of the invention.

Fig. 1 is a broken side elevation and part longitudinal sectional view of the unit in its operative relation to the phonograph record; Fig. 2 is a broken plan view of the unit with the case removed and parts appearing in section; Fig. 3 is a detached detail view of the armature element of the unit; Figs. 4 and 5 are detached plan views of two forms of resilient mounts for the armature.

The magnetic field is provided in the present disclosure by a small but relatively powerful permanent magnet 7 of the horseshoe type and a particularly important feature of this magnet is that it is supported in a flat, substantially horizontal position, close to the record surface indicated at 8. The actual support is shown as a hollow arm 9, which is suitably pivoted so as to swing, and raise and lower relative to the record, this arm carrying at its swinging end a plate or base 10 on which the U portion of the magnet is seated and to which it is suitably secured as by means of a screw 11 passed up through the base into a clamp plate 12 bridging the arms of the magnet. This provides a particularly well-balanced low-lying structure.

For concentrating the magnetic flux, pole pieces of generally C-shaped formation are provided as indicated at 13 and the same are secured to and connected in magnetic relation with the U-magnet by brackets 14 of magnetic material secured to the arms of

the magnet by screw bolts 15 and to the pole pieces by screws 16. These brackets are shown in Fig. 1 as angled to tilt the pole pieces away from the end of the magnet, so as to bring the armature which operates between the pole pieces into an inclined or slanting position.

The armature which is designated 17 is shown as a short straight rod or piece of magnetic material having a flattened and widened upper end 18 disposed between the upper set of pole tips 19 and a heavier base portion 20 disposed between the lower set of pole tips 21 and having a screw seat 22 for the screw 23 which clamps the needle 24 in the lower end of the same.

The armature is flexibly and resiliently mounted by means of a plate or strip 25, of material having the necessary flexibility and resiliency to center the armature and at the same time provide for the necessary movements of the same. Bakelite, a phenol condensation product in flexible sheet form, has been found suitable for the purpose, it being sufficiently stiff, but at the same time possessing enough flexibility and resiliency. In the illustration, the base of the armature is shown as having a reduced portion 26 extended through a central aperture 27 in the bakelite strip and riveted over the underside of the strip at 28 and the strip is shown as supported in spaced relation from the lower arms of the pole pieces by spacing washers 29 and rivets 30.

To render the central armature mounting portion of the bakelite piece sufficiently resilient, the same may be cross-slotted as indicated at 31 in Fig. 4, or the strip may simply be of relatively narrow or ribbon-like construction as shown in Fig. 5.

The thin bakelite plate or strip holds the armature properly centered and controlled for the desired vibration movements relative to the pole tips and at the same time acts as a brace tying the pole tips together in spaced relation.

The winding is shown as a single flat coil 32 supported in the hollows of the C-shaped pole pieces and having a bore large enough for the free movement of the upper portion 100

of the armature. The armature supporting strip 25 may be held by screws or the like instead of rivets 30 to enable removal of the armature and dismounting when that is desired.

5 The arrangement of the magnet in flat horizontal relation close to the record surface is particularly advantageous, bringing the mass of weight down close to the record and enabling the use of a short armature with a short stroke. The action is more effective electrically and the structure is better mechanically. The device may be easily assembled and because of its flat low-lying character takes up less overhead room in the phonograph cabinet.

10 What is claimed is:

1. An electric phonograph pickup, comprising a U-type magnet, means for supporting the same substantially horizontal and close above a record surface, a short straight armature bar, means for yieldingly mounting the same inclined downwardly and away from the ends of the magnet, a record engaging stylus at the lower end of said armature bar and a coil about the upper portion of said armature bar.

2. An electric phonograph pickup, comprising a U-type magnet, means for supporting the same in substantially flat horizontal relation, pole pieces inclined downwardly and away from the ends of said substantially horizontal magnet, a substantially straight armature bar, means for yieldingly supporting said armature bar in downwardly inclined relation to said pole pieces, a record engaging stylus carried by said armature bar and a winding inductively associated with the same.

3. In an electric phonograph pickup, comprising a U-magnet substantially C-shaped pole pieces secured in opposed relation to the ends of said magnet, a coil supported within said C-shaped pole pieces, a resilient mounting strip of insulating material secured across the tips of said pole pieces and an armature bar mounted on said supporting strip in co-operative relation to the pole pieces and the winding.

4. In apparatus of the character disclosed, the combination of a magnet structure, a winding carried thereby, a thin strip of phenol condensation product carried by the magnet structure and an armature supported by said strip in cooperative relation to the magnet structure and winding.

5. In apparatus of the character disclosed, a substantially horizontally disposed U-magnet, upwardly angled brackets at the ends of said magnet, pole pieces carried by said brackets, a downwardly inclined armature bar in cooperative relation to said pole pieces, a strip of resilient non-magnetic insulating material supporting said armature bar in

said relation and a winding surrounding the upper portion of said armature bar.

6. In an electro-magnetic phonograph pickup, a magnet structure, a magnetic stylus bar, a strip of sheet insulation resiliently supporting said stylus bar in cooperating relation to the magnet structure and a winding inductively associated with said stylus bar.

7. In an electro-magnetic phonograph pickup, a magnet structure having pole pieces, a stylus bar having a magnetic portion in cooperative relation to said pole pieces, a strip of flexible sheet phenol condensation product material resiliently supporting said stylus bar and a winding associated with said stylus bar.

8. In an electric phonograph pickup, comprising a U-magnet supported in flat horizontal relation, angled brackets extending from the ends of said magnet substantially C-shaped pole pieces supported by said brackets in spaced opposing relation, a winding mounted within the hollow of said pole pieces, a flat thin strip of sheet insulating material secured to said pole pieces and a short rigid straight armature bar rigidly secured at one end to said strip and projecting therefrom through the coil and interposed between the spaced pole pieces, said armature bar having a stylus socket in its lower end.

9. In apparatus of the character disclosed, the combination of a magnet and an electrically related cooperating vibrating member, a flat sheet of thin flexible insulating material, said vibrating member being rigidly mounted on a portion of said flat sheet material and securing means engaged with another portion of said flat sheet material for supporting the same with the vibrating member carried thereby in electrically cooperative relation with the magnet.

10. In apparatus of the character disclosed, the combination of a magnet structure, a strip of sheet insulation secured to said magnet structure, a vibrating member carried by said strip of insulating material and operatively related to the magnet structure, said vibrating member projecting from one face of the insulating strip and having a stylus socket opening to the opposite face of the strip and a stylus clamp associated with said socket.

11. In apparatus of the character disclosed, the combination of a magnet structure, a strip of sheet insulation secured to said magnet structure and a vibrating member carried by said strip of insulating material and operatively related to the magnet structure, said insulating strip having slots therein at opposite sides of the vibrating member.

12. As a new article of manufacture, a stylus mount for a phonograph pickup, comprising a flat strip of sheet insulating material and a stylus member rigidly secured to

an intermediate portion of said strip and projecting from one face of the same.

13. As a new article of manufacture, a stylus mount for a phonograph pickup, comprising a flat strip of sheet insulating material and a stylus member rigidly secured to an intermediate portion of said strip and projecting from one face of the same, said strip having openings therein at opposite sides of the stylus member.

14. In apparatus of the character disclosed, the combination of relatively movable electrically related members, one of small mass and intended to vibrate with respect to the other member, a support for said vibrating member including a strip of sheet insulation, said vibrating member being rigidly secured to an intermediate portion of said strip and said strip being rigidly held at opposite sides of said vibrating member.

15. In apparatus of the character disclosed, the combination of relatively movable electrically related members, one of small mass and intended to vibrate with respect to the other member, a support for said vibrating member including a strip of sheet insulation, said vibrating member being rigidly secured to an intermediate portion of said strip, said strip being rigidly held at opposite sides of said vibrating member and the cross-sectional dimensions of said strip being reduced at points in between the vibrating member and the points at which said strip is held.

In testimony whereof I affix my signature.
